UNITED STATES PATENT OFFICE.

IRA GUY NICKS, OF DENVER, COLORADO.

MECHANICAL TOY.

Application filed November 28, 1921. Serial No. 518,296.

To all whom it may concern:

Be it known that I, IRA G. NICKS, a citizen of the United States, residing at the city and county of Denver and State of Colorado, 5 have invented certain new and useful Improvements in Mechanical Toys, of which the following is a specification.

This invention relates to improvements in mechanical toys, and embodies a novelly 10 constructed and mounted hobby-horse, or analogous imitation rocking body, which is so hitched to a cart, in combination with novelly coacting elements therebetween, as to provide for the propulsion of the toy as 15 a bodily whole by the rocking actuation of the horse body or parts thereof.

It may be said at the outset that if in the 20 description and claims the term "horse" be employed alone, for the sake of brevity and simplicity, it is understood that the word is used in the sense of imitation horse, or for that matter any equivalent animal body or 25 analogous rocking body, and likewise where the term "cart" is employed, it is intended to cover any other appropriate type of vehicle as well.

The primary object of the invention has 30 been to devise such a combined toy, which is not only facilely operable by a child for self propulsion, but which also provides for a 35 rocking, bucking, or galloping motion of the horse, whether driven or ridden, whereby the general appearance and motions are more natural and life-like—hence more pleasurable to the child and associates.

Other objects and advantages of the 40 improvements will be so clearly apparent, as incidental to the following disclosure, that it would serve no useful purpose to further 45 enlarge upon the same initially, and with these prefacing remarks, therefore, reference will be immediately had to the accompanying drawings, forming a part of this application in illustration of a practical embodiment of the improvements, in which drawings like reference numerals designate the same parts in the several views, of which—

Figure 1 is a side elevational view of the 50 improved toy, certain parts additionally appearing in dotted outline to illustrate the changing positions of said parts;

Figure 2 is a top plan view thereof;

Figure 3 is a rear elevational view of the 55 cart section and a crank element for the axle thereof, one of the axle journals being partly broken away to illustrate a thrust ball bearing arrangement;

Figure 4 is a vertical cross-sectional view 60 through the horse section, taken along the line 4—4 of Figure 1, and illustrating a steering or guiding wheeled support which mounts the horse; and

Figure 5 is a local view, indicated by the 65 line 5—5 of Figure 1, showing in front elevation the application of a foot steering bar element, which additionally functions as pedaling means to assist in the rocking actuation of the horse.

In referring first to the improved horse 70 construction, it is to be understood that although the parts are illustrated as being formed of flat surfaced wood sections they may in actual practice be made of other suitable material and may be of rounded out contour, if desired, to more closely simulate the natural animal body.

The trunk or main body portion of the 75 horse consists of spaced side walls 10, the 80 edge openings between which may be closed by filler block sections where requisite or if desired for a rounded off and more finished appearance, the said side walls providing the chest-shoulder portions 11, the rump portions 12 and the fore and rear leg portions 13—14, and may also provide, in association 85 with an upper filler block 39 hereinafter mentioned, the pommel and cantle portions 16—17 of an imitation saddle body 15 with 90 accessories, which saddle body and accessories, as well as the bridle, mane of the 95 horse and other minor decorations or equipment, may be painted or otherwise applied to the horse body for ornamental purposes.

18 designates the tail member pivotally 95 connected at its upper end, as at 19, between the upper portions of the rump sections 12, and 20 designates the neck portion pivotally 100 supported, as at 21, between the chest-shoulder sections 11, the head of the horse 22 being integrally formed or joined with the neck, and a base extension 23 of the neck 105 being projected well down between the chest portions 11.

Each side wall of the chest portion 11 is 105 provided with a curved slot 24, struck on an

arc with the pivotal position 21 as its center, and the ends of a lateral pin 25 or paired pins, oppositely projected from the base extension 23 of the neck section, ride in 5 the said slots 24 to function as will herein-after appear.

26 and 27 respectively indicate driving and bridle reins connected at 28 to the head 22, which sets of reins are preferably formed 10 of rigidly stiff material, such as light metal bars or the equivalent, and 29 simply designates a foot rest or bar for the rider's feet, when mounted in the saddle, which cross bar extends transversely of the horse's fore- 15 legs 13.

From the base of the horse's rear leg sections, there is forwardly projected a steering gear support or bar 30 which pivotally mounts, as at 31, a transversely disposed 20 foot steering bar 32, providing straps or stirrup members 33, and this bar 32 further provides forwardly extending connecting rods 34, for coupling the steering bar with a guiding wheeled support for the horse 25 body. These coupling rods 34 may be attached in any suitable way, and I have illustrated their ends as being bent as offsets adapted to be projected through apertures in the bar 32 and the axle of the 30 wheeled support, which provides a convenient securing means for the said ends.

This guiding wheeled support comprises an axle 35, mounting a small pair of steering wheels 36 and also mounting the lower 35 bifurcate arms 37 of a vertical rod or post 38 which passes up into the horse body (see Fig. 4) and into a recessed filler block 39, the lower portion of the rod 38 being preferably rotatably supported by a fixed bot- 40 tom filler block 40 through the means of opposed bearing disks 41—42, maintained by the upper and lower cotter pins 43. However, other equivalent arrangements could be provided for all of the immedi- 45 ately foregoing features.

The rod 38 may, therefore, be free to rotatably oscillate in the horse body, under control of the steering gear, but otherwise the mounting is substantially rigid, so that 50 as the horse body is rocked, as hereinafter mentioned, there is also imparted thereto a slight loping-like or a rising and falling motion, owing to the ground pivotal bearing provided for by the supporting guiding 55 wheels 36.

Referring now to the cart or sulky construction, the axle 45 thereof provides the central crank arm 46 and the opposed side crank arms 47, which axle has a pair of 60 vertical rod members 48 furnishing upper and lower T-elements 49—50, the upper ones 49 providing fittings for coupling the rear ends of a pair of shafts 51 and an interposed rear shaft bar 52 therefor, while 65 the lower ones 50 provide journals for the

axle 45. These preceding elements may be of tubular formation, if desired, or otherwise.

The said lower T-elements 50 may each be formed with a ball race 53 (see the right side of Fig. 3) to provide for end thrust ball bearing journals for the rotatable axle 45, and at least one of the vehicle wheels 54 serves as a traction wheel which is fast to the axle to rotate therewith, while the other 70 wheel 54 is preferably revoluble freely on the axle, for obvious reasons, although it could be made fast to the axle if desired, as this whole arrangement is merely stated 75 optionally and could be altered in various 80 ways.

The extremities of the axle 45 are braced by a pair of angularly formed bracket supports, one of the legs 55 of each of which extends upwardly and forwardly for connection to the shafts 51, as at 56, while the shorter leg 57 is vertically upstanding and at its upper end is bent inwardly at 58 for attachment, as at 59, to the bottom of a seat 60. These angular brackets are apertured at their inverted apices to fit over the axle ends and are held in place, as by the nuts 61, with the inner hub faces of the wheels 54 turning in anti-frictional engagement with the balls of said ball bearings. 90

The seat 60 may be a long or short one and may be mounted in any suitable way, but as illustrated it is a long one and is supported from the shafts of the cart by means of divergent arms 62 extending immediately 100 underneath the seat, the outer ends of which arms 62 are bolted through the seat to the shafts 51, as at 63, while the inner ends thereof are secured together and to the seat and the rear shaft bar 52, as by a common 105 bolt 64, spacer blocks 65—66 being provided if desired, although not at all essential.

In coupling up the horse and vehicle, to attain the primarily desired ends of my improved combination toy, the shafts 51 of the sulky are connected with a pair of pivot pins 67, one of which projects laterally and outwardly from each of said chest sections 11, so that the body of the horse as a whole is pivotally associated with the shafts 51 115 110 to swing in a vertical plane with the pivot pins 67 as its axis.

This pivotal connection also permits of a slight tilting or vertical play of the shafts to compensate for the bodily rise and fall 120 of the horse, as distinguished from its rocking motion, caused by the forward and backward swing of the guiding wheeled support as will later appear, which vertical play of the shafts imparts a slight rocking motion 125 to the sulky similar to that occurring in real driving.

A pair of "long arm" actuating rods 70, one for each side of the horse body, are pivotally associated at their forward ex- 130

tremities with the ends of the lateral pin 25 projected from the neck base extension 23, which pin ends ride in and extend through the slots 24 of the chest sections 11 as before referred to.

Finally, a pair of "short arm" actuating rods 71 are pivotally connected at their rear ends to the crank arm 46 of the vehicle axle, and at their forward ends they are made fast to the lower end of the tail section 18, as by means of bolts 72 or equivalent rigid securing means. While I have shown a pair of such "short arm" actuating rods 71, it would appear that a single actuating bar 71 would in practice probably suffice, or a single bar with a bifurcate or bifurcated ends, if found to be expedient or desirable.

20 Operation.

The horse and working parts are shown in full lines at their intermediate positions, and as long as the reins connecting position is located above the axis 21, by pulling back 25 on the reins the actuation would cause a reversed or backing up operation, but if the reins connecting position 28 was immediately below the axis 21, by pulling back on the reins the actuation would cause the 30 starting of a forward operation. However to select a more definite position as a starting point to describe the cycle of operations, let it be first assumed that the parts are disposed as in dotted outline, when the 35 horse's jaw will be in its lowermost position lying in the plane of the line *a* cutting the axis 21, the tail member pivot 19 will be in its highest position lying in the plane of the line *b* cutting the axis 67, the lateral 40 pin 25 will be in its extreme rearmost position lying in the plane of the line *c* cutting the axis 21, the guiding wheels 36 will be in their rear positions *d*, the hind legs will be in their highest positions as indicated by *e*, 45 the central crank 46 will be in its forward position *f* and the paired cranks 47 will be in their rear positions *h*. It may be well to state that the reason that the pin 25, dotted in at the right, appears to be out of 50 the slot 24 is simply because the horse as a whole is then in its lowermost position and the slot 24 itself would be correspondingly lower, but its dotted illustration is omitted to avoid undue confusion of lines 55 on the drawings.

Starting then with the parts in the positions as in the dotted outline, the cycle of operations will be as follows:—

(1.) A downward and forward thrust 60 with the feet against the combined steering and pedaling bar 32 will cause all of the aforesaid parts respectively, to move to the positions as indicated by the designations *a'*, *b'*, *c'*, *d'*, *e'*, *g* and *i*, a downward and 65 rearward thrust being applied to the crank

46 in its forward position *f* by the "short arm" actuating rods 71, as will be apparent owing to the downward swing of the rump and tail member 18, it being remembered that the horse body is pivotally connected 70 to the shafts at 67. It will be noted that the "long arm" actuating rods 70 will now lie in a plane extending from the crank arms 47 positions at *i* to the lateral pin 25 disposed in the intermediate plane *c'*, the 75 crank 46 moving to the position *g*, and the reins connection 28 is now a trifle above the plane *a'* of the axis 21. The guiding wheeled support has also been moved slightly forward to the position *d'*, which 80 correspondingly elevates the horse as a bodily whole with a slight rising motion.

(2.) Upon now pulling back on the reins 26 (and it will be understood that all reference to the driving reins 26 apply also to 85 the bridle reins 27) there will be applied an operating force to cause all of the aforesaid parts, respectively, to move to the positions *a''*, *b''*, *c''*, *d''*, *h* and *f*, the crank arms 47 being pulled over forwardly a quarter revolution 90 from the position *i* to the position *f* by the forward pulling actuation of the rods 70 owing to the forward swing of the pin 25, carried by the base neck extension 23, 95 from the plane *c'* to *c''*, which latter movement has been caused by pulling the horse's head back to its position *a''*. It will now be noted that the "long arm" rods 70 lie in a plane extending from the crank arms 47 positions at *f* to the lateral pin 25 disposed in 100 the extreme forward plane *c''*, while the crank arm 46 and the rear ends of the "short arm" rods 71 lie at the position *h*, with the tail member 18 having been operated rearwardly to its full open position. 105

(3.) Now, upon pushing forwardly on the rigid reins element 26 (or 27) the head 22 will be swung forwardly and downwardly back to the position *a'*, the other parts, respectively, being likewise actuated back to their intermediate positions *b'*, *c'*, *d'*, *e'*, *i* and *g*, it being observed that the "long arm" rods 70 have this time functioned as "push" rods to force the crank arms 47 downwardly and rearwardly from the positions *f* to the positions *g*, while at the same time the crank arm 46 has been also revolved a quarter revolution to the position *i* from the position *h*, forcing the "short arm" rods 71 forwardly to partially 110 fold up the tail member 18 and raising the rump of the horse half way. 115

(4.) The reins connecting position 28 now passing immediately below the plane *a'*, by pulling back again on the reins 26 (or 27) 125 the horse's head is pulled downwardly to the position *a* again, moving the respective parts back to their initial dotted outline positions *b*, *c*, *d*, *e*, *f* and *h*, the rods 70 still functioning as push bars, during this quar- 130

ter revolution, forcing the crank arms 47 from the positions *g* to the positions *h*, and the crank arm 46 being moved forwardly and downwardly from the position *i* to the 5 position *f*, whereby the tail member 18 is fully closed and the rump section of the horse is moved upwardly to its highest tilted position, completing the cycle of operations which may be repeated indefinitely.

10 During these four quarter crank revolutions, it will likewise be obvious that the guiding wheeled support will be once shifted forwardly for its full swing and will be once shifted rearwardly for its full swing, causing 15 the horse body as a whole to twice rise and fall in addition to its rocking motion, providing for the life-like loping motions before referred to.

Considering the forward propulsion of the 20 combination toy, although it is apparent that backing up motions may be reversely accomplished, it may be briefly emphasized finally that the "long arm" rods 70 serve as actuating rods for the continuous revolution 25 of the crank element the said rods being operated by power applied to the horse's head in swinging the latter back and forth on its pivotal axis 21, and which rods function as "pull" rods from the position *h* 30 through *i* to *f* and as "push" rods from the position *f* through *g* to *h* whereas the "short arm" rods 71 function primarily to cause the rocking of the horse body as a whole serving as upwardly pushing rods from the position 35 *h* through *i* to *f* and as downwardly pulling rods from the position *f* through *g* to *h*; but the rods 71 additionally function as power applying rods to their crank 46 from the position *f* through *g* to *h* providing foot 40 power is applied in a downwardly and forwardly direction on the steering and pedaling bar 32 as the rump of the horse is moved from its uppermost to its lowermost tilting position.

45 As a matter of fact however when substantial momentum has been acquired to itself carry the parts over dead center the power applied by pulling and pushing on the reins may be reduced to a minimum and 50 a pulling force on the reins may alone suffice (without the pushing actuation thereof or without the pedaling actuation excepting perhaps in going up hills) so that I do not even necessarily limit myself to the use of 55 rigidly inflexible rein elements as to a large extent at least the operations could doubtless be satisfactorily accomplished even by the use of flexible rein elements.

It is also believed to be apparent that the 60 course of the combination toy may be guided readily by operating the steering bar 32 with the feet as would be indicated in dotted outline at Figure 2.

It is believed that the full advantages of 65 all of the foregoing features will be quite

apparent especially when we consider the desires of children and their leaning towards practical mechanically operated toys which have life-like appearance and motion.

While I have thus fully set forth my invention, it will be understood, however, that I do not wish to unnecessarily restrict myself to all of the details of the improvements exactly as disclosed, excepting as they may come within the terms of the ensuing claims, 75 or equivalent elements, and as fairly interpreted in the light of the specification if necessary, as it is obvious that various alterations might be made in future practice without necessarily departing from the spirit of 80 the invention. For instance, the single horse body or analogous element could be substituted for by a team, in which latter event a tongue might be employed instead of the 85 shafts as the vehicle hitching element.

What I do claim as new and patentable is:—

1. In a mechanical toy, the combination 90 with a vehicle having a hitching element providing wheels and propelling crank mechanism therefor, of a vertically rocking body member pivotally associated towards its forward end with said hitching element, a movable head element for said body member, actuating means between said movable head element and said crank mechanism, actuating means between the rear of said body member and said crank mechanism, and means for operating said movable head element back and forth. 95

2. In a mechanical toy, the combination 100 with a vehicle having a hitching element providing wheels and propelling crank mechanism therefor, of a vertically rocking body member pivotally associated towards its forward end with said hitching element, a movable head element and a pivotal tail element for said body member, actuating means between said movable head element and said crank mechanism, actuating means between said pivotal tail element and said crank mechanism, and means for operating said movable head element back and forth. 105

3. In a mechanical toy, the combination 110 with a vehicle having a hitching element providing wheels and propelling crank mechanism therefor, of a wheeled support, a vertically rocking body member mounted by said wheeled support and pivotally associated towards its forward end with said hitching element, connections between said wheeled support and said body member for advancing and withdrawing the former by the rocking of the latter, a movable head element for said body member, actuating means between said movable head element and said crank mechanism, and means for operating said movable head element back and forth 115 to operate said actuating means. 125

4. In a mechanical toy, the combination 130

- with a vehicle having a hitching element providing wheels and propelling crank mechanism therefor, of a wheeled support, a vertically rocking body member mounted by said wheeled support and pivotally associated towards its forward end with said hitching element, connections between said wheeled support and said body member for advancing and withdrawing the former by 5 the rocking of the latter, a movable head element for said body member, actuating means between said movable head element and said crank mechanism, actuating means between the rear of said body member and said crank 10 mechanism, and means for moving said head element back and forth.
5. In a mechanical toy, the combination with a vehicle having a hitching element providing wheels and propelling crank 20 mechanism therefor, of a wheeled support, a vertically rocking body member mounted by said wheeled support and pivotally associated towards its forward end with said hitching element, connections between said 25 wheeled support and said body member for advancing and withdrawing the former by the rocking of the latter, a movable head element and a pivotal tail element for said body member, actuating means between said 30 movable head element and said crank mechanism, actuating means between said pivotal tail element and said crank mechanism, and means for operating said movable 35 head element back and forth.
6. In a mechanical toy, the combination with a vehicle having a hitching element providing wheels and propelling crank mechanism therefor, of a vertically rocking body member pivotally associated to- 40 wards its forward end with said hitching element, a guiding wheeled support bodily mounting said rocking body member in rev- 45 oluble association therewith, connections between said wheeled support and said body member for advancing and withdrawing the former by the rocking of the latter, steering means for said connections, a movable head element for said body member, actuating means between said movable head 50 element and said crank mechanism, actuating means between the rear of said body member and said crank mechanism, and means for operating said head element back and forth.
7. In mechanical toys, the combination with a vehicle having a hitching element providing wheels and propelling crank mechanism therefor, of a vertically rocking body member pivotally associated towards 55 its forward end with said hitching element, a guiding wheeled support bodily mounting said rocking body member in revoluble association therewith, connections between said wheeled support and said body member for 60 advancing and withdrawing the former by 65

the rocking of the latter, steering means for said connections, a movable head element and a pivotal tail element for said body member, actuating means between said movable head element and said crank 70 mechanism, actuating means between said pivotal tail element and said crank mechanism, and means for operating said movable head element back and forth.

8. In a mechanical toy, the combination with a vehicle having a hitching element providing wheels and propelling crank mechanism therefor, of a vertically rocking body member pivotally associated towards its forward end with said hitching element, 75 a guiding wheeled support bodily mounting said rocking member in revoluble association therewith, connections between said wheeled support and the rear lower portion of said rocking member for advancing and 80 withdrawing the former by the rocking of the latter, combined steering and pedaling means mounted by said connections, a movable head element for said body member, actuating means between said movable head 85 element and said crank mechanism, actuating means between the upper rear of said body member and said crank mechanism, and means for operating said head element back and forth.

9. In a mechanical toy, the combination with a vehicle having a hitching element providing wheels and propelling crank mechanism therefor, of a vertically rocking animal body member pivotally associated 100 towards its forward end with said hitching element, a pivotal head element for said rocking member providing a base neck extension, a pivotal tail element for said rocking member, actuating means between said 105 pivotal tail element and said crank mechanism, actuating means between said base neck extension and said crank mechanism, and reins connected to said pivotal head element for swinging the latter and its base 110 neck extension back and forth.

10. In a mechanical toy, the combination with a vehicle having a hitching element providing wheels and propelling crank mechanism therefor, of a wheeled support, 115 a vertically rocking animal body member mounted by said wheeled support and pivotally associated at its forward end with said hitching element, connections between said wheeled support and said rocking member for advancing and withdrawing the former by the rocking of the latter, a pivoted head element for said rocking member providing a base neck extension, actuating means between said base neck extension and said crank mechanism, and reins connected to said pivotal head element for swinging the latter and its base neck extension back 120 and forth.

11. In a mechanical toy, the combination 130

with a vehicle having a hitching element providing wheels and propelling crank mechanism therefor, of a vertically rocking animal body member pivotally associated towards its forward end with said hitching element, a guiding wheeled support bodily mounting said rocking member in revoluble association therewith, connections between said wheeled support and said rocking member for advancing and withdrawing the former by the rocking of the latter, steering means for said connections, a pivotal head element for said rocking member providing a base neck extension, actuating means between said base neck extension and said crank mechanism, actuating means between the rear of said rocking member and said crank mechanism, and reins connected to said pivotal head element for swinging the latter and its base neck extension back and forth.

12. In a mechanical toy, the combination with a vehicle having a hitching element providing wheels and propelling crank mechanism therefor, of a vertically rocking animal body member pivotally associated towards its forward end with said hitching element, a guiding wheeled support bodily mounting said rocking member in revoluble association therewith, pivotal rigid connections between said wheeled support and the rear lower portion of said rocking member for advancing and withdrawing the former by the rocking of the latter, combined steering and pedaling means mounted by said pivotal rigid connections, a pivotal head ele-

ment for said rocking member providing a base neck extension, actuating means between said base neck extension and said crank mechanism, pivotal rigid actuating means between the upper rear of said rocking member and said crank mechanism, and reins connected to said pivotal head element for swinging the latter and its base neck extension back and forth. 40

13. In a mechanical toy, the combination with a vehicle having a hitching element providing wheels and propelling crank mechanism therefor, of a vertically rocking animal body member pivotally associated towards its forward end with said hitching element, a guiding wheeled support mounting said rocking member in revoluble association therewith, means for steering said wheeled support, a head element providing a base neck extension which is intermediate pivoted to the forward end of said rocking member, a lateral pin projecting from opposite sides of the lower portion of said base neck extension and freely extending through curved slots in said rocking member, pivotal rigid actuating means between said lateral pin and said crank mechanism, pivotal rigid actuating means between the upper rear of said rocking member and said crank mechanism, and reins connected to the head of said head-neck pivotal element for swinging said lateral pin back and forth in its curved slots. 50 55

In testimony whereof, I affix my signature.

IRA GUY NICKS.
